WILLIAM CHARLES SUTCLIFFE, OF LISMORE, NEW ZEALAND.

NON-REFILLABLE BOTTLE.

1,130,856.

Patented Mar. 9, 1915.

Application filed December 19, 1913. Serial No. 807,619.

To all whom it may concern:

To all whom it may concern:
Be it known that I, WILLIAM CHARLES SUTCLIFFE, a subject of the King of Great Britain and Ireland, residing at Lismore, in the Province of Canterbury and Dominion of New Zealand, have invented certain new and useful Improvements in Non-Refillable Bottles, of which the following is a specification.

10 This invention relates to bottles for containing spirits and other liquids, and consists in an improved irremovable closure for such bottles which allows the original liquid contents to be poured therefrom but
15 prevents the recharging of liquid into the bottles. Said closure may be fitted in the neck of a bottle formed or adapted to accommodate it, or may be contained in a collar or neck extension piece adapted to
20 be attached permanently to the neck of a bottle of standard shape, so as to form in effect a part of the bottle neck. The said closure comprises a centrally apertured washer, forming a ring seat for a valve, a
25 free disk which seats as a valve on said washer, a gullet block containing a domed pocket or cup shaped cavity for said valve and for a free rolling loading weight which bears on said valve; upper and lower ports
30 in alternate order and a collar groove in the sides of said gullet block offer tortile sigmoidal passages for liquid outflowing through said pocket. These four pieces, viz. the seating washer, the disk valve, the
35 spherical weight, and the pocketed and ported gullet block are assembled in proper relation, and after the bottle has received its original charge are fixed either in the neck of the bottle or in an adapter consisting of
40 a neck extension or collar capsule secured permanently upon the bottle.

The efficacy of the closure depends upon the shape, proportions, relational arrangement, and coaction of the said four pieces.

45 The means for securing said pieces in a bottle neck or in an adapter and for securing said adapter to a bottle, are accessory to the invention and are not separately claimed.

50 In the accompanying drawings, Figure 1 is a vertical sectional elevation showing the closure in which my invention consists,

fitted in the neck of a bottle specially formed to accommodate it; Fig. 2 is a top plan of same; Fig. 3 is a sectional elevation showing the closure adapted to a standard bottle by means of a crimped collar capsule which forms an extension of the bottle neck; Fig. 4 is a sectional elevation illustrating another form of adapter for holding the closure on the neck of a standard bottle; Fig. 5 is an exploded perspective view of the four pieces constituting the closure; Fig. 6 is a side elevation of the gullet block; Fig. 7 is a sectional elevation illustrative of another form of adapter or collar carrier for holding the closure on the neck of a bottle of that type which has a collar ring formed externally on it a little below the lip.

In the preferred application of the invention shown in Fig. 1, the bottle neck is formed to accommodate the closure; but the closure is substantially identical whether it is carried in the bottle neck or in an adapter or neck extension piece as shown in Figs. 3, 4, and 7. The structural modification of the bottle neck required to permit the fitting of the closure therein consists in providing a landing collar 1 upon which the washer 2 rests. 75 80

The washer 2 is preferably constructed of cork, rubber, or other material having some flexibility, but it may be constructed of a hard material provided that it sets neatly on the collar 1 and is finished to a fair face on the upper surface, and indented or grooved to receive the sprigs 13. 85

3 is a thin flat disk of glass, porcelain, mica, vulcanite, or like material having some rigidity. 4 is a marble or ball made of earthenware, glass, or other heavy material. The disk 3 and the ball 4 are accommodated in a domed shaped pocket 5 formed in the bottom of the gullet block. There is sufficient clearance allowed in the pocket 5 to permit the ball 4 and the disk 3 to move their positions, without however allowing the ball to come below the disk, when the bottle is canted or inverted, so as to allow a sufficient opening for the passage of liquid from the interior of the bottle through the hole 6 in the center of the washer 2 to discharge the contents of the bottle. The

cavity 5 is domed shaped, in order that the ball 4 will by gravity roll toward and press the disk 3 up to the washer 2 except when the bottle is canted sufficiently to enable its liquid contents to be poured out. Normally, therefore, the disk 3 is pressed down on the seating washer 2 by means of the ball 4 as indicated in the several figures, and when the parts are in that position, as shown in Figs. 1, 3, 4, and 7, the bottle is effectually closed. The gullet block (see Fig. 6) is grooved peripherally as shown at 7, the groove forming a belt around it. This belt groove provides a means of intercommunication between the radial ports 8 which are cut through the lower part of the wall of the pocket 5, and the external corner grooves 9 through which the belt groove 7 is open upwardly into the mouth 10 of the bottle neck.

It is important that the edges 11 of the ports 8 should be splayed outwardly, and that they shall extend into the pocket 5 above the plane corresponding to the diameter of the disk valve, and that the ports 8 and the ports 9 shall be in staggered relation to each other, and that the sides of the ports 8 and of the ports 9 shall be disposed angularly so as to form tortile sigmoidal passages which effectually check the insertion of any form of picking device through them after the closure has been fixed in the neck of a bottle or in an adapter secured thereon. The angular disposition of the edges 11 of the ports 8 is necessary for the purpose of directing any inflowing liquid against the upper surface of the disk 3. If, for instance, the bottle were inverted and an attempt made to fill it while in the inverted position, the disk 3 and the ball 4 being then lying in the upper part of the pocket 5 and the washer aperture 6 being open, the entering liquor will be directed by the angular port faces 11 so as to strike under the edges of the disk 3 and flood or force it back against the washer, thereby closing the bottle.

The gullet block is secured in the neck of the bottle by means of a spring ring 12. This ring is made of spring wire, its ends being angled off on the inner corners as shown at 13, Fig. 2. A groove in the bottle neck is provided to accommodate this ring. It is compressed a little and pushed into place and allowed to spring out home into said groove after the closure has been placed in the bottle, following on the original filling of the bottle. The difficulty of removing this spring ring after it has expanded into the groove makes any tampering with the closure unprofitable. The difficulty of extracting the ring 12, and thereafter drawing the closure is so great that a bottle fitted in the manner described is for commercial purposes non-refillable. The gullet block

may be secured or luted in the bottle neck or adapter by means of a suitable cement which is not soluble in the liquid with which the bottle is charged.

To facilitate assembling the parts correctly and entering them neatly into the bottle neck when the gullet block is fixed in the bottle neck as shown in Fig. 1 two or more sprig pieces 13 (five are shown in the drawings) are formed on the lower end of 75 the gullet block. When the washer 2 is of relatively soft material they may be pressed into it, but if it is of hard material indentations or a concentric groove may be formed in it to accommodate them. It is 80 advantageous to make these sprigs of such form that they will lightly grip the washer 2 to facilitate the assembling of the pieces and to obviate risk of pinching the edge of the disk 3 accidentally in forcing the parts 85 into position in the bottle neck or adapter. Though shown also in Figs. 3 and 7, the sprigs 13 are not ordinarily used in the constructions shown in those figures.

As shown in the drawings the gullet block 90 is formed with five ports 8 and 9. It will suffice however if it be made with two, three, or four such ports. It is inconvenient to make it with a greater number of ports than five for an ordinary sized bottle, but it will operate satisfactorily if made with such greater number of ports. It is necessary that the proportions be such that the ports 8 and 9 and the angular positions of the walls thereof are in such mutual relation 95 that it is impracticable to insert a snake or picker down through them for the purpose of interfering with the valve 6. The five-ported arrangement shown in the drawings 100 is very effective for bottle necks of ordinary size, as it is practicable with that number of ports to arrange them and form their walls so that a tortile sigmoidal passage way only 105 is offered for passage of liquid through and around the gullet block. The diameter of the valve disk 3 is a little less than the internal diameters of the lower part of the pocket 5, and the spherical weight 4 is of 110 less diameter than the valve disk 3 and is a free fit for the upper part of the pocket 5. The walls of the pocket 5 are segmental to insure that the weight 4 will roll against the valve 3 and close it except when the bottle 115 is canted beyond a horizontal position.

The mouth 10 of the bottle or adapter may 120 be fitted with a cork, crown capsule, or other device for the purpose of effectually closing it against leakage during transit, guarding against evaporation of contents, and preventing ingress of dust.

The arrangement shown in Fig. 3 is a 125 convenient one for adapting the closure to a bottle neck of standard form. As it has been proposed heretofore to fix closures to the necks of bottles by means of a crimped 130

collar of pewter or other soft metal as shown in this view, no claim is made in respect of this adapter, which consists of a skirt piece 14 having an internal mouth rim 15 adapted 5 to take over the top edge of the gullet block. The skirt 14 is crimped at 16 close around a collar on the bottle neck thereby to draw down the skirt around the bottle neck and secure it tightly thereon. In this case the 10 washer 2 sets directly on the top of the bottle neck.

In the case of a bottle with a rim neck as shown in Fig. 4, a closure may be conveniently accommodated in an adapter 20 which 15 is formed with an internal neck rim 21 to take over the top of the gullet block, and an externally flanged lower rim 22 to set on the top of the bottle neck. The diameter of the adapter 20 is made somewhat more than the 20 internal diameter of the bottle neck in order to provide a ledge 23 upon which the washer 2 may set. The flange 22 is secured by means of a crimped band 24 to the rim 25 on the neck of the bottle. A packing ring may 25 be inserted between the rim 25 and the flange 22. Fig. 7 illustrates a similar arrangement in which the extension fitting is adapted to fit a bottle neck having a ring 26 externally below the lip 27 of the bottle 30 neck. The adapter 20 is in this case secured to the bottle by means of a crimped band of soft metal 24 similar to the band 24 shown in Fig. 4, and the washer 2 sets on the top of the bottle neck. The bottle is filled with 35 its original charge of liquid before the closure is inserted into its neck or attached to it according to the method shown in Figs. 2, 4, and 7 respectively. The closure once fitted is intended to remain as a permanent fitting 40 or attachment in the bottle so that at no time may the bottle be recharged through the neck. The gullet block may be made of hard material capable of maintaining its form. In practice it would be made of glass or 45 porcelain. It is desirable that no part of the fitting except the check ring 12 should be of metal, when the contents of the bottle are such as would tend to cause corrosion. Normally, when the bottle is erect or canted, un- 50 til it is canted to a plane about 20° below horizontal the disk 3 sets over the seat washer 2, closing the central aperture 6, therein, the spherical weight 4 bearing down the disk 3; and there is then no passage 55 through which liquid may flow into the bottle. When the bottle is inverted or canted beyond about 20° below the horizontal position, the pressure of the spherical weight 4 on the disk 3 is relieved and the weight and 60 the disk may then fall back into the pocket 5; thereupon liquid may flow past the disk 3 and through the pocket 5 and sigmoidal passageways 8, 7, 9, out of the bottle. While 65 the bottle is canted or inverted it is not practicable to introduce more than a few

drops of liquid into it, because the entering liquid is directed under the edge of the disk 3 in entering the pocket, causing the disk 3 to rise and seat on the washer 2 and so close entry to the bottle. The air locked in the 70 bottle cannot be spilled, and also operates to prevent refilling.

What I claim as my invention and desire to secure by Letters Patent is:

1. A bottle closure of the class described, 75 comprising a centrally apertured washer forming an inner valve seat and adapted to fit tight within a bottle neck, a free disk valve disposed outwardly of the washer to seat against the same, a free weight dis- 80 posed outwardly of the valve for engagement therewith, and a gullet block disposed outwardly of the washer in the bottle neck, said block having in its inner end a socket accommodating with clearance the weight 85 and valve and providing in its walls an outer seat for the valve, the block being provided further with ports communicating with the socket inwardly and outwardly of the outer valve seat and with tortuous 90 passage ways leading outwardly from the said ports through the outer end of the block.

2. A bottle closure of the class described, 95 comprising a centrally apertured washer forming an inner valve seat and adapted to fit tight within a bottle neck, a free disk valve disposed outwardly of the washer to seat against the same, a free weight dis- 100 posed outwardly of the valve for engagement therewith, and a gullet block disposed outwardly of the washer in the bottle neck, said block having in its inner end a socket accommodating with clearance the weight 105 and valve and providing in its walls an outer seat for the valve, the block being provided further with ports communicating with the socket inwardly and outwardly of the outer valve seat and with tortuous 110 passage ways leading outwardly from the said ports through the outer end of the block, the portions of the ports disposed outwardly of the outer valve seat being splayed.

3. A bottle closure of the class described, 115 comprising a centrally apertured washer forming an inner valve seat and adapted to fit tight within a bottle neck, a free disk valve disposed outwardly of the washer to seat against the same, a free weight dis- 120 posed outwardly of the valve for engagement therewith, and a gullet block disposed outwardly of the washer in the bottle neck, said block having in its inner end a tapered 125 socket having its walls converging out- wardly and adapted to accommodate with clearance the weight and valve, the diameter of the socket being equal at a point intermediate of its ends to the diameter of the valve whereby an outer seat is provided 130

at this point for the valve, the block being provided further with ports communicating with the socket inwardly and outwardly of the outer valve seat and with tortuous 5 passage-ways leading outwardly from the said ports through the outer end of the block.

Copies of this patent may be obtained for five cents each, by addressing the "Commissioner of Patents, Washington, D. C."

In testimony whereof I have affixed my signature in presence of two witnesses.

WILLIAM CHARLES SUTCLIFFE.
